UNITED STATES PATENT OFFICE.

CHARLES POLLARD, OF WEMBLEY, LONDON, AND ARTHUR BURROUGHES EVANS, OF LEEDS, ENGLAND, ASSIGNORS TO GEORGE MANN & COMPANY LIMITED, OF HUNSLER, LEEDS, ENGLAND.

PRINTING MACHINERY.

1,210,202.

Specification of Letters Patent. Patented Dec. 26, 1916.

Application filed March 30, 1915. Serial No. 18,034.

To all whom it may concern:

Be it known that we, CHARLES POLLARD, residing at 21 Berkhamstead avenue, Wembley, London, N. W., England, and ARTHUR BURROUGHES EVANS, residing at Highbank House, Harehills Lane, Leeds, in the county of York, England, both subjects of the King of Great Britain and Ireland, have invented certain new and useful Improvements in 10 Printing Machinery, of which the following is a specification.

The present invention relates to printing machinery of the type in which the sheets to be printed are fed down a feed board situated on the upper side of an impression cylinder.

In printing machinery with continuously revolving cylinders for printing one or more colors, of the type described, it is customary 20 for the impression cylinder to make, after the revolution or revolutions necessary for printing the sheet, an extra revolution for the purpose of carrying the printed sheet forward to the delivery mechanism which 25 delivers the sheet printed side up on the delivery board, this extra revolution being necessitated by reason of the fact that the sheet which is being delivered has to cross the plane in which the next sheet has to be 30 fed.

The present invention consists in the provision of an additional delivery cylinder or the like, carrying grippers, the sheet being delivered from the impression surface to this 35 delivery cylinder during the last revolution of the former required for printing, and re-delivered to the impression surface at a later period of the working of the machine, so that the sheet to be delivered can pass between the feed-board and the impression cylinder at a time when no sheet is being fed.

The invention further consists in the improved delivery mechanism for printing machinery hereinafter described.

45 Referring to the accompanying drawings: Figure 1 is a sectional side elevation showing parts of the printing machine constructed according to the invention. Fig. 2 is an enlarged elevation of the impression cylinder showing the means for operating the

grippers. Fig. 3 is a detail view of one pair of grippers, while Fig. 4 is an end view showing the end of the impression cylinder and the fixed parts operating the grippers.

In the form of the invention illustrated 55 the machine comprises an impression cylinder *a* on which the sheet is carried during the printing operation and an off-set cylinder *3* carrying rubber printing surfaces or the like on which the design to be printed is 60 impressed by the cylinder *4* carrying stereotypes or other printing surfaces. The impression surface *a'* of the impression cylinder *a* occupies more than half the periphery of the cylinder. The sheet to be printed is 65 fed down a feed-board *b*, and seized by the automatically operated grippers *c'*, the operation of the grippers being effected in a known manner by the slide *d*, secured to the gripper shaft *e*, and the two pins *f'*, *f*². The 70 sheet having been seized by the grippers *c'*, is in this example to be impressed with two colors or two designs, for which process one complete revolution and a portion of a second revolution, of the cylinder *a* are required. In this example, during the first revolution of the cylinder *a*, one color or design is impressed on the sheet by one of the 75 printing surfaces, on the printing cylinder *3*, and during the second revolution of the cylinder *a*, the second color or design is impressed on the sheet from the printing surface *2* on the cylinder *3*. After the second color or design has been impressed, the sheet is released by the grippers *c'*, at a point corresponding approximately with the line of 80 centers of the cylinder *a* and the delivery cylinder *g*, and is seized by the automatically operated grippers *h* mounted on a shaft *k* carried by the cylinder *g*, and operated in a known manner by cams (not shown). The sheet is then carried by the grippers *h* for one complete revolution of the cylinder *g*, this cylinder being approximately equal in diameter to the cylinder *a*, and is re-delivered to a second set 85 of grippers *c*², preferably individually mounted upon the gripper shaft *e*, and operated by means of levers *l* mounted on a shaft *m*, which is operated by means of 90 95 100

a lever *n* and runner *o* by the cam *p*. The grippers *c*² hold the sheet against a portion of the grippers *c*', and carry it forward from the point at which it is delivered from the cylinder *g* to the point of delivery indicated by the strippers *r*, at which point the grippers *c*² release the sheet, which is delivered a second time from the cylinder *a*, and carried forward by known means to the usual delivery mechanism. The grippers *c*² are constrained by springs (not shown) to press upon the grippers *c*', except when they are operated by their own actuating mechanism, as described above.

It will be seen that as there are two colors or designs to be printed, and for this purpose two revolutions only of the cylinder *a* are required to form a complete cycle of the machine, a second sheet will have been seized by the grippers *c*', and imprinted with one color or design before the first sheet is re-delivered to the grippers *c*², and that the two sheets will be carried together under the feed-board *b* as far as the point of final delivery indicated by the strippers *r*. At this place, the second or inner sheet continues to be held to the cylinder *a*, and goes forward to receive its second printing, while the first or outer sheet is released, and goes forward to the delivery mechanism. It is not essential that the cylinder *g* should be approximately equal in diameter to the cylinder *a*, as the same object may be obtained if the cylinder *g* is of a diameter which is a multiple of the diameter of the cylinder *a*, and carries a corresponding number of sets of grippers. The surface of the cylinder *g* may be of any suitable material to carry the printed sheet face inward without smearing.

Having now described our invention, what we claim as new and desire to secure by Letters Patent is:

1. In printing machinery, in combination, an impression cylinder, an impression surface on said cylinder, means for feeding sheets to said impression surface, means for final delivery of said sheets from said cylinder, and a carrying cylinder adapted to receive sheets from said impression surface, and re-deliver said sheets to said impression surface.

2. In printing machinery, in combination, an impression cylinder, an impression surface on said cylinder, a feed-board at the upper side of said impression cylinder, means for stripping completely printed sheets from said cylinder, and a carrying cylinder adapted to receive sheets from said impression surface and re-deliver said sheets to said impression surface.

3. In printing machinery, in combination, an impression cylinder, an impression surface on said cylinder, a feed-board at the

upper side of said impression cylinder, means for stripping completely printed sheets from said cylinder, said feed-board and stripping means being approximately in a plane tangential to said impression cylinder, and a carrying cylinder adapted to receive sheets from said impression surface, and re-deliver said sheets to said impression surface.

4. In printing machinery, in combination, an impression cylinder, an impression surface on said cylinder, means for feeding sheets to said cylinder, means for final delivery of said sheets from said impression cylinder, grippers adapted to hold sheets on said impression surface during printing, and grippers adapted to hold sheets on said impression surface during their travel from said carrying cylinder to said delivery means.

5. In printing machinery, in combination, an impression cylinder, an impression surface on said cylinder, means for feeding sheets to said impression cylinder, means for final delivery of said sheets from said impression cylinder, a carrying cylinder adapted to receive sheets from said impression surface and re-deliver said sheets to said impression surface, and grippers on said carrying cylinders adapted to hold a sheet on said carrying cylinder during the feeding of the next sheet to said impression cylinder.

6. In printing machinery, in combination, an impression cylinder, an impression surface on said cylinder, a printing surface co-operating therewith, means for feeding sheets to said cylinder, means for final delivery of said sheets from said cylinder and a carrying member adapted to receive sheets from said impression surface, and re-deliver said sheets from said impression surface.

7. In printing machinery, in combination, an impression cylinder, an impression surface on said cylinder, a printing cylinder having two printing surfaces co-operating with said impression cylinder, means for feeding sheets to said impression cylinder, means for final delivery of said sheets from said impression cylinder, and a carrying cylinder adapted to receive sheets from said impression surface, and re-deliver said sheets to said impression surface.

8. In printing machinery, in combination, an impression cylinder, an impression surface on said cylinder, a printing cylinder having two printing surfaces co-operating with said impression cylinder, means for feeding sheets to said impression cylinder, means for final delivery of said sheets from said impression cylinder, a carrying cylinder adapted to receive sheets from said impression surface, and re-deliver said sheets to said impression surface, grippers on said

impression cylinder adapted to hold sheets for two revolutions on said impression cylinder, and grippers adapted to hold sheets on said impression cylinder during their travel from said carrying cylinder to said final delivery means.

In testimony whereof we have signed our

names to this specification in the presence of two subscribing witnesses.

CHARLES POLLARD.
ARTHUR BURROUGHES EVANS.
